Att'y.

UNITED STATES PATENT OFFICE.

JOHN C. McAULIFFE, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

1,330,202.

Specification of Letters Patent. Patented Feb. 10, 1920.

Application filed March 1, 1918. Serial No. 219,786.

To all whom it may concern:

Be it known that I, JOHN C. McAULIFFE, a citizen of the United States, residing at New York, in the county of New York, 5 State of New York, have invented certain new and useful Improvements in Telephone-Exchange Systems, of which the following is a full, clear, concise, and exact description.

10 This invention relates to telephone exchange systems and more particularly to such systems employing trunk circuits for interconnecting telephone lines terminating at different switchboards.

15 The object of this invention is to provide improved signaling means for such systems.

In accordance with a feature of this invention, the incoming end of a trunk circuit is provided with a signaling device which, 20 when a link circuit is connected with the outgoing end thereof, is operated continuously to furnish a guard signal, which remains so operated after the trunk circuit has been connected with a telephone line until the receiver thereof is removed from the 25 switchhook to furnish a ringing signal, and which is intermittently operated to furnish a disconnect signal when the link circuit is disconnected from the outgoing end of the 30 trunk circuit.

For a more complete understanding of this invention reference should be had to the following description considered in connection with the accompanying drawing 35 illustrating one embodiment thereof.

As shown in the drawing a telephone line A terminates at one switchboard where it is connected with a link circuit B. A trunk circuit C extends from the first to a second 40 switchboard and serves, when the link circuit B is connected therewith, to extend the connected telephone line A to the second switchboard. The trunk circuit C, through its incoming end, may be connected with the 45 telephone line D terminating at the second switchboard. All apparatus shown to the left of the dotted line 2-2 is associated with the first switchboard or "A" operator's position, while that shown to the right of 50 this line is associated with the second switchboard or "B" operator's position.

The subscriber A having initiated a call in the usual manner and the cord circuit B

having been connected therewith, the "A" operator may actuate listening key 6 to connect the operator's telephone set with the telephone line. Upon being advised that subscriber A desires to be connected with the line which terminates at the second switchboard, the "A" operator restores the 55 listening key 6 to normal position and communicates over an order wire circuit (not shown) with the "B" operator of the second switchboard and receives a trunk assignment. 60

Assuming the trunk assignment to be trunk circuit C, the "A" operator inserts calling plug 7 of the cord circuit B into jack 8 of the trunk circuit C, whereupon calling supervisory lamp 9 is lighted over a 70 circuit from battery through the lamp 9, resistance 10, sleeve contacts of the plug 7 and the jack 8 and resistance 11 to ground. Trunk relay 12 is also operated over a circuit from battery through the winding of 75 calling supervisory relay 13, ring contacts of the plug 7 and jack 8, the windings of the trunk relay 12, and tip contacts of the jack 8 and the plug 7 to ground. Calling supervisory relay 13 does not now operate 80 because of the high resistance of the left-hand winding of the trunk relay 12. The trunk relay 12 in operating causes the lighting of lamp 15 and the operation of relay 16. The lamp is lighted over a circuit from battery through the lamp 15, normal contact and lower winding of relay 17, and contact of the trunk relay 12 to ground. The lower winding of relay 17 is such that the relay 85 does not receive sufficient current to cause 90 it to open its normal and close its alternate contacts. Relay 16, in operating, opens its left-hand and closes its right-hand contact.

The lighting of the lamp 15 serves as an indication to the trunk or "B" operator that the "A" operator has connected with the assigned trunk circuit. The "B" operator may thereupon insert plug 18 of the trunk circuit C into jack 19 of the telephone line D, it being assumed that connection is desired with telephone line D. Upon the insertion of the plug 18 into the jack 19, relay 17 of the trunk circuit and cutoff relay 20 of the telephone line are operated over a circuit from battery through the lamp 15, 100 upper winding of relay 17, sleeve contacts 105

of the plug 18 and the jack 19 and the winding of the cutoff relay 20 to ground. Relay 17 in operating opens its normal contact and closes its alternate contacts. The lamp 15 6 remains lighted.

Subscriber D may be signaled in any desired manner. Upon the removal of the receiver from the switch hook, supervisory relay 25 is operated over a circuit from battery through the winding of relay 25, ring contacts of the plug 18 and the jack 19, out over one side of the line, through the switchhook contact, back over the other side of the line, tip contacts of jack 19 and the plug 18, 10 and the upper alternate contact of relay 17 to ground. Relay 25, in operating, connects the low resistance left-hand winding of relay 26 in parallel with the high resistance left-hand winding of trunk relay 12. The resistance in circuit with the calling supervisory relay 13 is thereby reduced, permitting the operation of this relay. Relay 13 in operating establishes a shunt circuit, including resistance 27, about the lamp 9 15 which is thereby effaced. Relay 26 operates, establishing a shunt circuit for the lamp 15, which may be traced from battery through the right-hand contact of relay 16, the right-hand winding and the contact of relay 26, 20 lower alternate contact of relay 17. This shunt circuit is of low resistance, so that the lamp 15 is effaced.

At the conclusion of the conversation, subscriber D, in restoring the receiver to the switchhook, causes the release of relay 25, removing the left-hand winding of relay 26 from parallel relation to the left-hand winding of trunk relay 12, thereby increasing the resistance in circuit with the calling 25 supervisory relay 13. This supervisory relay 13 thereupon releases its armature, causing the calling supervisory lamp 9 to be lighted to furnish a disconnect signal. Subscriber "A" in restoring the receiver to the switchhook causes the lighting of the usual answering supervisory lamp (not shown). The lighted supervisory lamps of the cord circuit B serve as disconnect signals, whereupon the "A" operator may withdraw the 30 plug 7 from the jack 8. Trunk relay 12 thereupon releases, and in releasing opens the energizing circuit of relay 16. Relay 16 thereupon opens its right-hand contact, which is in circuit with the relay 26. Relay 26 thereupon releases its armature, opening the shunt circuit about the lamp 15. The closure of the left-hand contact of relay 16 35 upon the release thereof, establishes an intermittent shunt circuit for the lamp 15, which may be traced from battery through interrupter 28 and resistance 29, left-hand contact of relay 16 and the lower alternate contact of relay 17. The lamp 15 is thereupon 40 intermittently lighted to furnish a disconnect signal to the "B" operator, who may 45

thereupon withdraw the plug 18 from the jack 19, restoring all apparatus to normal condition.

From this brief description it will be clear that the lamp 15 is continuously lighted 70 when the plug 7 is inserted into the jack 8, to serve as a guard signal, and after the plug 18 has been inserted into the jack 19 the lamp remains continuously lighted until the called subscriber removes the receiver 75 from the switchhook, thereby serving as a ringing signal. At the conclusion of the conversation when the plug 7 is withdrawn from the jack 8, the lamp 15 is intermittently lighted to serve as a disconnect signal. 80

What is claimed is:

1. A telephone exchange system comprising a trunk circuit extending from a first to a second switchboard, a telephone line terminating at a second switchboard and connected with the trunk circuit, a link circuit at the first switchboard, a signaling device at the second switchboard operating upon the connection of the link circuit therewith, a relay in the trunk circuit responsive to the closure of the telephone line upon the removal of the receiver from the switchhook for stopping the operation of the signaling device, and a relay responsive to the disconnection of the link circuit from the trunk circuit to cause the intermittent operation of the signaling device.

2. A telephone exchange system comprising a trunk circuit extending from a first to a second switchboard, a telephone line terminating at a second switchboard and connected with the trunk circuit, a link circuit at the first switchboard, a signaling device at the second switchboard operating upon the connection of the link circuit therewith, a relay in the trunk circuit responsive to the closure of the telephone line upon the removal of the receiver from the switchhook for stopping the operation of the signaling device, and interrupter mechanism included in circuit with the signaling device upon the disconnection of the link circuit from the trunk circuit to cause the intermittent operation of the signaling device. 105

3. A telephone exchange system comprising a trunk circuit extending from a first to a second switchboard, a link circuit at the first switchboard, a telephone line terminating at the second switchboard, a signaling device in the trunk circuit, a relay in the trunk circuit energized in response to the connection of the link circuit therewith for causing the operation of the signaling device, means for connecting the trunk circuit with the telephone line, a relay in the trunk circuit energized over the connected telephone line for controlling the signaling device, and an interrupter mechanism brought into operative relation with the signaling device by the deenergization of the 110

first relay following the disconnection of the link circuit from the trunk circuit for causing the intermittent operation of the signaling device.

5 4. A telephone exchange system comprising a trunk circuit extending from a first to a second switchboard, a telephone line terminating at the second switchboard, a signal-link circuit at the first switchboard, a signaling device in the trunk circuit, a relay in the trunk circuit energized in response to the connection of the link circuit therewith, a second relay in the trunk circuit co-operating with the energized relay for causing 10 the operation of the signaling device, a circuit

established by the connection of the trunk circuit with the telephone line for causing the energization of the second relay and for maintaining the signaling device operated, and an interrupter mechanism 20 brought into operative relation with the signaling device by the deenergization of the first relay following the disconnection of the link circuit from the trunk circuit for causing the intermittent operation of 25 the signaling device.

In witness whereof, I hereunto subscribe my name this 16th day of February, A. D. 1918.

JOHN C. McAULIFFE.
